RAILWAY JOURNAL LUBRICATOR

James J. Hennessy, New York, N. Y.

Application June 30, 1934, Serial No. 733,229

17 Claims. (Cl. 308—84)

This invention relates to lubricators for axle bearings and particularly railway vehicle journal bearings.

Patent No. 1,704,743, issued to the present inventor, illustrates a journal bearing lubricator comprising a pump located in the box cellar or reservoir and a distributor adjacent the journal, the pump piston being actuated to deliver oil to the distributor by a contact rod extension held by a spring in engagement with the adjacent wheel hub. The pump actuator is intermittently forced inwardly against the spring pressure by lateral play of the wheel and journal relative to the journal box and pump. This lateral play, however, is not uniform and to prevent irregularities therein from causing the delivery to the journal of widely varying quantities of lubricant, the extent of reciprocation of the contact rod is limited by a bushing frictionally seated in the contact rod housing and positioned between spaced stops on the rod.

Where the movement of the pump actuator is limited as described above, only a fraction of the lateral play of the hub is utilized and, accordingly, the contact rod must be carefully adjusted to properly cooperate therewith. Due to unavoidable variations in the dimensions of the journal boxes, in the thicknesses of the hub liners, and in the positioning of the lubricator in the box cellar, means must be provided permitting accurate adjustment of the contact rod after installation of the lubricator. While the contact rod limiting bushing shown in the above patent will be automatically adjusted after the device has been in operation for a substantial length of time, no means is provided for immediately insuring the proper delivery of oil when the device first begins to operate after installation or after the box hub liner has been changed.

An important object of the present invention is to provide means facilitating quick and accurate automatic adjustment of the contact rod actuator in a limited delivery lubricator of the above type.

Another object is to provide means for adjusting and limiting reciprocation of the contact rod actuator, which means is controlled from outside the journal box.

These and other more detailed objects hereinafter appearing are attained by the structures illustrated in the accompanying drawing, in which—

Figure 1 is a vertical section through a locomotive driving box and cellar and taken on the line 1—1 of Figure 2.

Figure 2 is a vertical section taken on the line 2—2 of Figure 1.

Figure 3 is a view corresponding to Figure 1 but showing a modification.

Figure 4 is a sectional view corresponding to Figure 3 but showing another modification.

In Figures 1 and 2, the invention is shown applied to a locomotive driving box including side walls 1, for engaging the underframe pedestal jaws (not shown), and the crown bearing brass 10 resting upon the journal portion 3 of the axle. Positioned in the lower portion of the driving box beneath the journal is the cellar 4 deepened at its inner portion to form the lubricant reservoir 5.

Located within the reservoir 5 is a pump body 6 having a suction inlet 6a and provided at the bottom with a screen 7 and leading at the top past ball check 8 to the horizontal pump cylinder 9. Receiving the cylinder 9 is a chambered housing 10 extending horizontally through the cellar to the rear wall 11 thereof. The pump piston 12 is actuated within cylinder 9 by a contact rod 13 extending through a cylindrical chamber 13a in the outer part of housing 10 and through end wall 11. A spring 15 constantly urges the piston and contact rod outwardly and maintains the contact rod in engagement with the adjacent face of the wheel hub 14. It will be understood that during normal operation of the vehicle the wheel and journal will have lateral play relative to the journal box, causing reciprocation of the pump piston to draw lubricant from the reservoir past ball check 8 and then force the same past ball check 16 through passages 17 and 18 and the tube 19 to the distributor 20 maintained adjacent the journal. The distributor may be in the form of a pan packed with suitable waste or felt material. The details of the pump and distributor referred to are more fully described in co-pending application Serial No. 558,719, filed August 22, 1931 in the name of the present inventor.

The contact rod 13 passes through a fixed collar 21 in chamber 13a and a bushing 22 closely fitting this chamber but slideable therein. A spring 23 compressed between collar 21 and bushing 22 urges the bushing outwardly towards the annulus 24 on the contact rod. A bushing 25 frictionally secured in chamber 13a is in position to be engaged by annulus 24 to prevent complete ejection of the contact rod from casting 10 under the influence of springs 15 and 23 when the lubricator is removed from the box.

Located in a chamber 26 within the housing 55

18 and extending above and parallel to the chamber 13a and cylinder 9 is a plunger 27 having its left end portion hollow and seating a coiled spring 28 and telescopingly receiving the inner end of 5 a pin 29. A small pin 30 extends through the plunger 27 and a slot 31 in pin 29 and prevents disassembly of the latter and plunger 27 under the influence of spring 28. Pin 29 has a tapering outer end 32 for engaging a detent 33, in the 10 operative position shown, and urging the same downwardly against bushing 22 to frictionally secure the same within the chamber 13a against movement by spring 23. The bushing, when so secured, will be engaged by a small pin 34 projecting laterally from the contact rod to limit outward movement of the rod. A spring 35 is compressed between shoulder 36 at the left hand end of chamber 26 and the left hand end of hollow plunger 27 and urges the plunger and 15 pin assembly towards the right and away from its operative association with the detent 33. The plunger 27 has a knob 37 at its right hand or inner end which is disposed to be engaged by the cover plate 38 of the journal box, when the latter is in its normal closed position, to maintain 20 the pin 29 in engagement with the detent 33, this engagement being cushioned by the spring 28. The cover is secured in position by a bolt 39 extending through lugs 40 on the cellar. 25

30 When the cover plate 38 is removed from the driving box, spring 35 will cause the frictional pressure on bushing 22 through detent 33 to be released and the piston spring 15 may then force the contact rod outwardly as far as permitted by 35 the hub 14. The bushing, when released, will be held against collar 24 by spring 23. When the cover plate is replaced, the bushing will be secured in its assumed position by detent 33, pin 29 and plunger 27. In case the hub is not 40 at its innermost position when the loose bushing is thus set, the first inward movement of the hub will force the collar 24 and bushing 22 inwardly notwithstanding the pressure applied through detent 33. Reciprocation of the contact 45 rod will then be restricted to the distance between the pin 34 and the adjacent edge of bushing 22, this reciprocation being substantially constant regardless of the amount of lateral play of the wheel and journal relative to the journal 50 box.

In Figure 3, the housing 41 within the cellar 42 corresponds with the lower part of casing 10 in the previous form, including the pump cylinder and a part spaced therefrom within which 55 is located the loose bushing 43 and the pump actuating contact rod 44. Projecting above the housing 41 is a perforated boss 45 receiving the detent 46. Frictional pressure is applied to the bushing 43 through the detent 46 by means of 60 a lever 47 pivoted to an arm 48 on the housing 41 and a rod 49 extending through the floor of the cellar 42 and engaging the spacer bar 50. The cellar floor is built up around the rod, as at 65 51, to prevent the loss of lubricant through the opening provided in the cellar floor for the rod. A compressed spring 52 engages the collar 53 on the rod and urges the same downwardly so that when the spacer plate 50 is removed, frictional pressure on the bushing 43 will be released, 70 permitting extension of the contact rod as previously described.

In Figure 4, the sliding bushing 54, corresponding to the bushing 22 in Figures 1 and 2 and 43 in Figure 3, is frictionally positioned within housing 55 by means of mechanism operatively as-

sociated with the spacer as in Figure 3. Secured to the floor of the cellar 56 adjacent the housing 55 is an upright tube 57 with an internal fixed bushing 58. Slidable within bushing 58 is a plunger 59 urged downwardly against spacer 60 through an opening in the floor of cellar 56 by a spring 61 compressed between the fixed bushing 58 and the shouldered lower portion of the plunger.

Plunger 59 carries a strip 62 of spring material which extends up over the side of tube 57 and is then flexed downwardly under spring tension between the tube and pump housing 55. A nubbin 63 on strip 62 projects into a slot in the side of housing 55 and, in the illustrated position of the parts, yieldingly engages the sliding bushing 54 to frictionally position the same so as to limit the reciprocation of the piston actuator 64 as described above. The extremity of strip 62 engages a lip 65 at the lower end of a slot 66 in the inner side of tube 57.

When the spacer 60 is removed, the plunger 59 and the spring 62 will move downwardly under the influence of spring 61 and the extremity of strip 62 will slide down the inclined edge of lip 65, causing further flexing of the spring strip by cam action and withdrawal of nubbin 63 from engagement with bushing 54. When the plunger is forced upwardly by the spacer or any other means, the nubbin 63 will be again moved against bushing 54 by spring 62. A pin 68 extending through tube 57 and a slot 67 in plunger 59 prevents disassembly of the plunger, coiled spring 61, and tube when the spacer is removed.

In each of the forms, the loose bushing and frictional detent are illustrated as separate parts, but these may be rigidly connected in a one-piece device, in which case the detent will be positioned in a suitable slot in the housing. Adjustment of the contact rod to properly cooperate with the hub will be quickly, accurately, and automatically effected. Whenever the lubricator is removed or changed, the pump actuating contact rod will automatically adjust itself. The loose bushing is controlled preferably by a member which will be placed in its operative position after the lubricator has been assembled with the box. The proper adjustment of the lubricator requires no efforts other than the closing of the box lid or the replacement of the spacer bar.

Obviously the contact rod limiting bushing may be similarly controlled by other means and also the invention may be modified as to details for attaining substantially similar results. The position and details of the lubricator itself are not essential and, in fact, any suitable lubricating mechanism utilizing a reciprocating actuator may be substituted for the pump shown. The exclusive use of all such modifications as come within the scope of the appended claims is contemplated.

I claim:

1. In combination, a vehicle journal lubricant cellar structure having a removable wall part, a journal lubricator including an actuating member operable by an adjacent element movable relative thereto during normal operation of the vehicle, and means rendered operable by assembly of said removable part with the rest of the structure for limiting the extent of movement of said actuating member.

2. In combination, a journal lubricant cellar having an opening, a lubricator insertable through said opening and including a reciprocating actuator and mechanism for limiting the reciprocation

of said actuator, means for securing said mechanism in a predetermined limiting position, and a closure member for said opening disposed to engage said means to normally maintain said mechanism in said limiting position.

5. In combination, a journal lubricator including a longitudinally reciprocating actuator, a device limiting the reciprocation of said actuator, means for securing said device in operative position, a spring urging said securing means away from its operative association with said device, and a member normally maintaining said securing means in said operative position and manually movable to render said limiting device inoperative.

10. In combination, a journal lubricant cellar having a closure member, a lubricator retained in said cellar by said member and including a reciprocating actuator, a variable device for limiting the reciprocation of said actuator, means controlled by said closure member for releasably securing said device in the predetermined limiting position, and means normally urging said securing means away from its operative association 25 with said limiting means whereby said limiting means will be rendered inoperative when said closure member is removed.

20. Lubricating mechanism for a vehicle journal including an actuator, an adjustable device limiting the extent of movement of said actuator, and means for securing said limiting device in an operative position, said securing means being releasable from outside the mechanism to render said limiting device inoperative, and said actuator being operatively associated with said limiting device in a manner to permit adjustment of said limiting device thereby when said securing means is inoperative.

25. In combination, a vehicle journal lubricant cellar, a journal lubricator inside said cellar including a housing and an actuator, a device movably mounted in said housing for limiting the reciprocation of said actuator, means urging said actuator and said device towards one extreme of movement, and releasable structure normally securing said device in an actuator limiting position against the influence of said means, said limiting device being automatically adjustable during initial operation of the vehicle after said structure has been rendered operative and said structure maintaining said device in the adjusted position against said means.

30. In combination, a lubricator including a housing and a longitudinally reciprocating actuator therein, a fixed stop adjacent said actuator and a cooperating stop on said actuator spaced from said fixed stop, a bushing in said housing and between said stops, a spring urging said bushing towards one of said stops, a device for applying frictional pressure to said bushing to yieldingly secure the same in the predetermined limiting position, and means for manually releasing said frictional pressure to permit adjustment of said bushing by means of said actuator.

35. Structure as defined in claim 7 with the addition of a spring in said housing normally urging said actuator outwardly, said first mentioned spring maintaining said bushing against the outer of said stops when the frictional pressure on said bushing is released.

40. In combination, a vehicle journal lubricant cellar, a journal lubricator therein including a lateral motion actuator for engaging the adjacent wheel hub and having spaced stops, a de-

vice located between said stops for limiting the reciprocation of said actuator, spring means urging said actuator against the wheel hub and said device against the outer of said stops, and releasable mechanism for yieldingly securing said device in the limiting position determined by the innermost movement of the wheel hub.

45. In combination, a vehicle journal lubricant cellar having a closure member, a lubricator therein including a housing and a hub contacting actuator, there being a fixed stop adjacent said actuator and a stop on said actuator spaced from said fixed stop, a loose bushing in said housing between said stops, a device for applying frictional pressure to said bushing to secure the same in position and thereby limit movement of said actuator, and means controlled by said closure member for releasing said frictional pressure to permit adjustment of said bushing.

50. In combination, journal lubricating mechanism including a reciprocating actuator and a chambered housing, a variable device for limiting the reciprocation of said actuator, means for securing said device in the predetermined limiting position comprising a plunger in said housing, a pin engaging said device, a spring connecting said plunger and said pin, and a movable member normally engaging said plunger and maintaining said pin operatively associated with said device.

55. In combination, journal lubricating mechanism including a lubricant pump having a cylinder and a longitudinally reciprocating piston actuator, spaced stops on said actuator, a bushing surrounding said actuator between said stops and of less length than the distance therebetween, a detent loosely mounted in said housing adjacent said bushing, and manually controllable means for urging said detent against said bushing to frictionally maintain the latter in the predetermined limiting position in said housing.

60. A railway locomotive driving box including a spacer, a lubricator in said box including a reciprocating actuator, a device for limiting the reciprocation of said actuator, means for securing said member in a predetermined limiting position and including said spacer, and a spring urging said means away from its securing position and rendering said device inoperative when said spacer is removed.

65. In combination, a vehicle journal lubricator including a reciprocating actuator, a variable device for limiting the reciprocation of said actuator, and yielding means independently operable to facilitate adjustment of said device.

70. In combination, a vehicle journal lubricator including a reciprocating actuator, a variable device for limiting the reciprocation of said actuator, structure for yieldingly maintaining said device in the predetermined limiting position, and cam action means for releasing said device from the influence of said structure to facilitate adjustment of said device.

75. In combination, a railway journal box, a journal, a lubricator therefor including a body, a removable closure for said body, a pump and a pump actuating member arranged for engagement with an element movable with the journal, a device for limiting the pump actuating movement of said member, said pump, member and device being located in said body, and means operable by the application and removal of said closure for rendering said device effective or ineffective respectively.

17. In combination, a railway journal box, a journal, a lubricator therefor including a body, a pump and a pump actuating member arranged for engagement with an element movable with the journal, a device for limiting the pump actuating movement of said member, said pump, member and device being located in said body,

there being an element having a sliding fit in an aperture in the wall of said body and holding said device in functioning position, and means operable from the exterior of said body, while said lubricator is applied to said journal, for rendering said element effective or ineffective.

JAMES J. HENNESSY.
